(57) **CLAIM**

I claim the ornamental design for a sand traction wheel, as shown and described.

DESCRIPTION

FIG. 1 is a top perspective view of a sand traction wheel showing my new design;

FIG. 2 is a left side elevational view thereof;

FIG. 3 is a right side elevational view thereof;

FIG. 4 is a top plan view thereof, the bottom plan view being identical to the top plan view;

FIG. 5 is a front elevational view thereof, the rear elevational view being identical to the front elevational view; and,

FIG. 6 is a top perspective view thereof showing the sand traction wheel attached to the rear horizontal support pipe of a beach chair. The broken lines are for illustrative purposes only and form no part of the claimed design.

In the drawings, the stippling is for shading purposes only and forms no part of the claimed design.
